UNITED STATES PATENT OFFICE.

EDWARD WESTON, OF NEWARK, NEW JERSEY, ASSIGNOR TO WESTON ELECTRICAL INSTRUMENT COMPANY, OF WAVERLY PARK, NEW JERSEY, A CORPORATION OF NEW JERSEY.

DESIGN FOR AN INDEX NEEDLE OR HAND FOR ELECTRICAL MEASURING INSTRUMENTS.

41,349.

Specification for Design.

Patented May 2, 1911.

Application filed November 9, 1909. Serial No. 527,118. Term of patent 14 years.

To all whom it may concern:

Be it known that I, EDWARD WESTON, a subject of the King of Great Britain, residing in Newark, county of Essex, and State of New Jersey, have invented a new, original, and ornamental Design for Index Needles or Hands for Electrical Measuring Instruments, of which the following is a specification, reference being had to the accompanying drawing, forming part thereof.

The figure is a perspective view of an in-

dex needle or hand for electrical measuring instruments, showing my new design.

I claim:—

The ornamental design for an index needle or hand for electrical measuring instruments, as shown.

EDWARD WESTON.
